UNITED STATES PATENT OFFICE

HAIG SARAFIAN, OF NEW YORK, N. Y., ASSIGNOR TO NOVELITE, INC., A CORPORATION OF NEW YORK

ILLUMINATED DISPLAY

Application filed October 12, 1929. Serial No. 399,112.

My present invention, while having a wide range of applicability, is especially adapted for embodiment in an illuminated display fixture or sign board for use in store windows, theatre lobbies and other locations where compactness and ready portability are desired.

An object of the invention is to provide a sign-carrying display device of striking and attractive appearance, equally well adapted for either day or night display.

Another object is to provide a device of this character which is light in weight, rugged and durable in construction, self-supporting in any desired location of use and unlikely to be toppled over or inadvertently damaged by casual handling or jostling.

More specifically these results are accomplished despite the use of inherently fragile mechanism such as neon tubes on the face of the sign.

In a preferred embodiment of the invention a sign board proper is supported upon a relatively heavy anti-tilting pedestal and is formed with suitable framing openings in which illuminated selectively changeable display signs are mounted.

The sign board and pedestal are so designed that in themselves, they afford an attractive mounting and border for the signs but for purposes of further enhancing the beauty of the device, particularly at night, the sign elements are framed with one or more border-forming neon tubes or equivalent devices.

The tubes are sunk in the face of the sign to avoid casual injury. Rather than resort to expensive rabbeting or grooving operations to provide a protective tube channel, the sign

border frame is formed in two concentric sections, spaced apart sufficiently to define a border channel for the tubes and rigidly held together by a concealed connective strip which serves as the bottom of the tube groove.

This strip also prevents moisture or foreign matter from finding ready access to the lamp casing behind the panel and fouling the switches or other electrical terminals which may be housed therein.

The invention may be more fully under-

stood from the following description in connection with the accompanying drawings, wherein:

Fig. 1 is a front elevational view of a display device embodying the invention;

Fig. 2 is a side elevational view thereof with part of the lamp casing broken away and in section;

Figs. 3 and 4 are transverse sectional views on the lines 3-3 and 4-4, respectively, of Fig. 1;

Figs. 5 and 6 are enlarged sectional details on the lines 5-5 and 6-6, respectively, of Fig. 1;

Fig. 7 is a transverse sectional detail on the line 7-7 of Fig. 1, and

Fig. 8 is a section through Fig. 7 on the line 8-8.

In the drawings the reference numeral 10 designates a relatively massive pedestal from which rises the upright sign board or panel consisting of an outer frame member 11, and an inner frame member 12. These frame members are spaced concentrically, one within the other and connected by rigid metal strips 13, nailed or otherwise secured at 14 to the backs of the respective frames and serving to secure the frames together and define with them an open front channel or groove 34, for the reception of the ornamental neon border tubes 15, which will be more fully described hereinafter.

An open-front lamp casing 16, is secured at its edges to the outer framing member 11, this lamp casing being bottomed on the pedestal and having a hinged door 17 at one side to provide access to the lamps 18, flasher switch 19, and other mechanisms within the casing.

The door 17 also permits the ready removal of the sign units which are displayed within the framing spaces defined by the inner panel 12 and by suitable cross members 20 which connect the uprights of this frame.

Preferably certain of the upper framing spaces such as 21 are provided with glass windows 22, the edges of the glass resting against rearwardly facing shoulder 23 at the opening and being held in place by brads 24 or equivalent devices.

Displays of any appropriate type may be mounted behind windows 22, and illuminated by lamps 18. For illustrative purposes changeable letter sign units 25 are shown, 5 of the type disclosed in the prior Patent #1,662,407 to Herrschaft, granted the thirteenth day of March, 1928. These signs are supported upon horizontal rails 26 and may be entered between the rails by a lateral 10 sliding movement when the door 17 is open.

An additional display may be arranged in the lower framing opening 27. This display consists of a flexible sign card 28, held between the flat glass plates 29. The edges of 15 the card and glass plates are received in a recess 30 at the back of the sign and are held in position by retaining rails 31 nailed or otherwise secured at 32 to the member 12 and the cross bars 20.

20 It will be noted that the pedestal 10 is more or less ornamental. The concentric frames 11 and 12 may also be decorated in any appropriate manner and additional ornamentation may be afforded by cap or 25 crown pieces 33 mounted upon the top of the outer frame 11.

This display thus constructed provides an attractive frame for the illuminated signs, the attention-compelling qualities of which 30 are enhanced by the flasher switch for the lamps within the casing 16. In order to avoid needless complexity of illustration I have not shown the conventional circuits for these lamps but they are connected by well 35 known means in series or parallel through the flasher switch.

In order, however, that the striking appearance of the sign may be further enhanced and its advertising as well as artistic value may be increased, I do not rely 40 upon the opaque mounting and framing means alone for decorative purposes, I rather employ a luminous border frame in the form of a neon tube 15 disposed in the channel 34 defined between the frames 11 and 12 and the connective strips 13.

An advantage of this luminous framing means is the fact that even when the sign 50 is displayed in obscure corners where the opaque decorative panelling and pedestal do now show up conspicuously, the luminous display is still surrounded by a handsome and sharply defined border.

By mounting the neon tube in the channel 55 34, it is effectively protected against casual injury, such for instance, as might be caused by persons jostling the sign in a theatre lobby or by careless handling in moving it about in store windows.

60 Numerous means for mounting the tube within its channel may be resorted to and the tube may either comprise a single luminous element or may comprise a plurality of independent sections of tubing. The color 65 of the tube or tubes may either harmonize

or contrast with the colors of the illuminated sign and where a plurality of framing tubes are used, these tubes may harmonize or contrast in color with each other.

One convenient and satisfactory method 70 of securing the tube in place and a method which materially facilitates assembly operations or repair operations is herein illustrated. In accordance with this method the tube is formed in two generally U shaped 75 sections with their longer intermediate portions lying in the vertical runs of channel 34, and their legs lying in the top and bottom horizontal portions of the channel. Each end of each tube is provided with a 80 rearwardly extending terminal section 15^a, the upper terminals being series connected as at 15^b and the lower terminals having leads 15^c to any suitable source of electrical 85 energy (not shown).

The tube sections are embraced at a number of points by spring clips 35 of generally 90 U shape having flat intermediate portions 35^a and curved arms which embrace the tube. The extremities of these arms are flared at 95 35^b, so that the clips snap over the tubes as they are forced into position to straddle or embrace them. The clips may be lined with cushioning material 36, in order to protect the tubes. In assembly the clips are 95 snapped over the tube and in this position are of a width to approximately fill the channel 34. The tube and clips are then emplaced in the channel and the clips are slid along the tubes until their flat intermediate 100 portions hook over fingers 37, fixed to and offset from the plate 13. When assembly has thus been accomplished it is impossible for the tube and clips to fall out as a unit due to the engagement of the clips with the 105 fingers or hooks, and it is impossible to remove the tubes from the clips since the walls of the channel 34 prevent sufficient spreading of the clips to permit escape of the tubes therefrom.

110 It will thus be seen that the tubes are effectively guarded against both casual injury or inadvertent displacement, yet may be deliberately removed for purposes of repair or inspection.

115 As noted above, the wiring connections are not in themselves my invention but it will be obvious that many attractive combinations of electrical hook-ups may be employed to flash the border tubes or the sign 120 illuminating lamps simultaneously or separately and that either set of luminous elements may be continuously illuminated while the other set is switched on and off by the thermostatic flasher 19 or equivalent device. For the sake of convenience I have shown a hand switch 40 arranged within the lamp casing 16 so all switch mechanism as well as the bulbs and tubes are entirely self-contained upon the unit and the unit may, 125 130

without disturbing any of the mechanism therein, be hooked up to an ordinary wall plug or any other conventional outlet.

It will thus be seen that there is herein described an apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention what I claim as new and desire to secure by Letters Patent is:—

1. In a display device of the class described, a sign board having an opening therein, means to mount a sign at the opening, a tubular luminous border member substantially surrounding the opening, the sign board being recessed to receive and protect such border member, and means for illuminating the sign and the border member.

2. A display sign including a pair of substantially concentric frame members disposed one within the other and having their edges spaced apart, concealed connective means disposed behind the frames rigidly connecting them in properly spaced relationship and serving as a bottom for the groove defined between the frames, means to display a sign in the inner frame and a luminous border tube housed within the groove.

3. A display sign including a pair of substantially concentric frame members disposed one within the other and having their edges spaced apart, concealed connective means disposed behind the frames rigidly connecting them in properly spaced relationship and serving as a bottom for the groove defined between the frames, means to display a sign in the inner frame and means to removably mount a border member in the groove.

4. A display sign including a pair of substantially concentric frame members disposed one within the other and having their edges spaced apart, concealed connective means disposed behind the frames rigidly connecting them in properly spaced relationship and serving as a bottom for the groove defined between the frames, means to display a sign in the inner frame and a luminous border element removably mounted in the groove and protected by the walls thereof.

5. A display sign including a pair of substantially concentric frame members disposed one within the other and having their edges

spaced apart, concealed connective means disposed behind the frames rigidly connecting them in properly spaced relationship and serving as a bottom for the groove defined between the frames, means to display a sign in the inner frame, a luminous border tube housed within the groove, fastener elements 70 slidable along the tube and means fixed to the connective means for engagement with the fastening elements.

6. A display sign including a pair of substantially concentric frame members disposed one within the other and having their edges spaced apart, concealed connective means disposed behind the frames rigidly connecting them in properly spaced relationship and serving as a bottom for the groove defined between the frames, means to display a sign in the inner frame, a luminous border tube 75 housed within the groove, fastener elements 80 slidable along the tube and means fixed to the connective means for engagement with the fastening elements, said slidable fasteners being incapable of being disengaged by a direct outward movement.

7. A display sign including a pair of substantially concentric frame members disposed one within the other and having their edges spaced apart, concealed connective means disposed behind the frames rigidly connecting them in properly spaced relationship and serving as a bottom for the groove defined between the frames, means to display a sign in the inner frame, a luminous border tube 85 housed within the groove, fastener elements 90 slidable along the tube and means fixed to the connective means for engagement with the fastening elements, said slidable elements comprising spring clips adapted to snap over the tube and of such a width that the walls 95 of the groove hold them against sufficient spreading to permit release of the tube while the clips are in the groove.

8. An illuminated display unit including a pedestal, a panel rising therefrom, a lamp 110 case behind the panel, means for removably mounting translucent display signs in the panel, a luminous border tube encircling the sign elements and means on the panel to receive and protect said tube.

9. An illuminated display unit including a pedestal, a panel rising therefrom, a lamp case behind the panel, means for removably mounting translucent display signs in the panel, a luminous border tube encircling the sign elements and means on the panel to receive and protect said tube, the tube being releasably secured to lie substantially flush with the outer face of the panel.

10. In a display device, a tubular display element, said display device having a groove therein to receive and protect said tube, fastener elements slidable along the tube and means arranged in the bottom of the groove 125 for engagement with said fastener elements.

11. In a display device, a tubular display element, said display device having a groove therein to receive and protect said tube, fastener elements slidable along the tube, means arranged in the bottom of the groove for engagement with said fastener elements, said slidable elements comprising spring clips adapted to snap over the tube and of such a width that the walls of the groove hold them against sufficient sliding to permit release of the tubes while the clips are in the groove.

12. In a display device, a tubular display element, said display device having a groove therein to receive and protect said tube, fastener elements slidable along the tube, means arranged in the bottom of the groove for engagement with said fastener elements, said slidable elements comprising spring clips adapted to slide over the tube and of such a width that the walls of the groove hold them against sufficient sliding to permit release of the tubes while the clips are in the groove, the clips when engaged with the engaging means at the bottom of the groove being incapable of disengagement by a direct outward movement.

13. A display device including a frame having a border, a sign member within said frame surrounded by said border and a tubular luminous member encircling said sign and encompassed by said border, said member being mounted inwardly from the face of said border.

14. A display device including a frame having a border, a sign member within said frame surrounded by said border and a tubular luminous member encircling said sign and encompassed by said border, said sign and member being mounted inwardly from the face of said border.

15. A display device including a frame having a border, a sign member within said frame surrounded by said border and a tubular luminous member encircling said sign and encompassed by said border, said sign and member being mounted inwardly from the face of said border, said member being positioned between the face of the border and the sign.

16. A display device including a sign, a frame therefor extending forwardly therefrom and including a border and a tubular luminous member mounted within said frame and encircling said sign and being positioned forwardly from the sign and rearwardly from the face of the border.

17. A display device including a sign, a frame therefor extending forwardly therefrom and including a border and a tubular luminous member mounted within said frame and encircling said sign and being positioned forwardly from the sign and rearwardly from the face of the border and securing means for said member carried by said frame.

18. A display device including a border

frame member, a second frame member disposed within said border frame member and spaced therefrom, a sign member disposed within the inner frame member, and a tubular luminous member disposed within the space formed between said frame members.

19. A display device including a border frame member, a second frame member disposed within said border frame member and spaced therefrom, a sign member disposed within the inner frame member, a wall member disposed in the space between said frame members, defining with said frame members a channel, and serving as a backing for said channel, and a luminous tube disposed within said channel.

Signed at New York, in the county of New York and State of New York, this 10th day of October, A. D. 1929.
